Primary Examiner — Kevin K Rudzinski*Assistant Examiner* — Evans David Delesline(74) *Attorney, Agent, or Firm* — Oliff PLC(57) **CLAIM**

The ornamental design for an article of jewelry, as shown and described.

DESCRIPTION

FIG. 1 is a front elevational view of the article of jewelry, showing the new design;

FIG. 2 is a rear elevational view thereof;

FIG. 3 is a top plan view thereof;

FIG. 4 is a bottom plan view thereof;

FIG. 5 is a left-side elevational view thereof;

FIG. 6 is a right-side elevational view thereof; and,

FIG. 7 is a front, right-side, top perspective view thereof. The black-shaded areas in the views depict areas that are colored black. The grey shading in the drawings indicates a contrast in appearance. The broken lines depict portions of the article of jewelry that form no part of the claimed design.

1 Claim, 7 Drawing Sheets(56)
